UNITED STATES PATENT OFFICE.

JOHN HEISSENBERGER, OF NEW YORK, N. Y.

CUTLERY.

No. 927,532.

Specification of Letters Patent. Patented July 13, 1909.

Application filed July 6, 1906. Serial No. 324,997.

To all whom it may concern:

Be it known that I, JOHN HEISSENBERGER, a citizen of the United States, and a resident of New York, in the county of New York and State of New York, have invented certain new and useful Combination Knives with Sharpeners, of which the following is a specification.

My invention relates to improvements in 10 cutlery, and particularly to pocket knives, the object of the invention being to provide a detachable sharpening medium which may readily be incorporated in the handle of a tool, so that at any time the tool may easily 15 be sharpened with facility and without loss of time.

Another object of the invention, is to provide such a sharpening medium which may be carried in the tool handle without rendering the same of inconvenient or bulky 20 size, or awkward for use, will not weaken the structure of the handle, and will be a valuable adjunct to the tool.

With the above objects in view, my invention consists in pivoting one of the handles or grips of the tool to the frame or body of the tool, in mounting a removable whetstone or sharpening medium in such handle, and in providing means for locking the free 25 end of the handle to the frame; and the invention comprises certain other novel features of construction, combination and arrangement of parts substantially as herein set forth.

In the accompanying drawings: Figure 1, is a side elevation of an ordinary pocket knife equipped with my improvements, one of the handles or grips being swung open to show the sharpening medium therein. Fig. 40 2, is a front edge view of the same. Fig. 3, is a transverse sectional view of the knife on line *a*—*b* of Fig. 1. Fig. 4, is a broken detail view of a portion at one end of the knife, to show the spring catch for securing the handle 45 in closed position. Fig. 5, is a transverse sectional view of one of the handle members with an improved form of sharpener therein.

The knife illustrated in the accompanying 50 drawings is of the usual pattern, having the rigid face plate A and the pivoted face plate B, forming the handle and also having the pair of side plates 9 and 10, forming the frame, and the blades D and E, pivoted 55 therebetween. Tips C and F are secured to

the side plates at one end, one of the tips (C) having beveled or undercut edges 3, and the other tip (F) having its inner edge also beveled, as shown at 8, the two tips forming what is known as the "head" of the knife. 60 A rivet pin 11, passes through the side plates at the front edge and serves to secure the blade - actuating spring H therebetween. Passing through the side plates at the end opposite the head, is a pivot pin 2, to which 65 is pivotally secured the casing or handle member B, the opposite or free end of said handle member being beveled at an incline to engage the undercut portion of the head. Within said casing is arranged a sharpener 70 6, and such sharpener may be of stone, metal, mineral composition or any other suitable abrading material. Struck up from the side plate 9, near the end at the head of the knife, is a spring tongue 12, having a lip 13, 75 adapted for engagement with the recess in the handle when the handle is closed. The other grip or handle member is not hollow like the one just described, but has a strip of sharpening material 4, secured to its lower 80 face. This handle portion has a beveled edge to engage the undercut head at one end, and in its opposite end is formed a hole or socket 1 to form a bearing for the head of the rivet or pin 2, and thereby lock the handle in 85 place. A notch 5, is formed in the lower edge at the end of said handle so that the same may be readily removed. The handle piece B, on its inner face and near its free end is formed with the lug or stop 14, which holds 90 the file in proper position.

In the sectional view, Fig. 5, I have shown an improved form of sharpening medium, which comprises a metallic reinforcing strip 6^a, having a layer of abrasive material 6 and 95 6^b, secured to each face thereof. This sharpener is especially valuable when used in connection with a knife, as it is light and compact, and may provide both fine and coarse abrading surface. The sharpener 4 100 may be readily employed for sharpening the blades of other knives when required.

I do not wish to limit myself to the application of a sharpener to a knife only, as the device may as well be applied to other articles of cutlery, and different materials for the sharpening medium may be employed. 105

From the foregoing description taken in connection with the drawings, it is evident that I have accomplished all the objects 110

herein set forth, and have provided a practical and desirable attachment for knives and similar edged tools.

I claim:

- 5 1. A pocket knife having beveled undercut tips, sides to the knife, one of said sides being removably secured to the knife and having an inclined end to engage beneath the undercut tip, the opposite side being in the form of a hollow casing to form a receptacle, said hollow casing being pivotally secured to the knife and having a beveled end to engage beneath the undercut tip.
- 10 2. A pocket knife having beveled undercut tips, sides to the knife, one of said sides being removably secured to the knife and having an inclined end to interlock with the undercut tip, the opposite side being hollow to form a receptacle, said hollow side pivoted to the end of the knife and having a beveled end to engage beneath the undercut tip, and a spring catch upstanding from the body of the knife to engage and hold the hollow side closed.
- 15 20 25 3. A pocket knife substantially as shown

and described having end pieces provided with beveled undercut tips, sides forming the handle to the knife, said sides having beveled inclined ends for coöperation with said tips, one of said sides being hollow, and said hollow side being mounted to be swung open to expose the under face thereof.

4. A pocket knife substantially as shown and described having end pieces provided with beveled undercut tips, sides forming the handle to the knife, said sides having beveled inclined ends for coöperation with said tips, one of said sides being hollow, and said hollow side being mounted to be swung open to expose the under face thereof, and means 35 upstanding from the body of the knife to hold said hollow side closed.

Signed at New York, in the county of New York, and State of New York, this second day of July A. D. 1906.

JOHN HEISSENBERGER.
